[57] **CLAIM**

The ornamental design for a catheter bag holder, as shown and described.

DESCRIPTION

FIG. 1 is a top, front perspective view of a catheter bag holder embodying my design;

FIG. 2 is a front elevational view of the design as shown in FIG. 1 in an expanded or open posture;

FIG. 3 is an enlarged fragmentary view of the surface of the catheter bag holder as shown in FIG. 2;

FIG. 4 is a rear elevational view of the catheter bag holder as shown in FIG. 1; and

FIG. 5 is a bottom plan view of the catheter bag holder as shown in FIG. 1.

FIG. 1

FIG. 2

FIG. 3

FIG. 4

FIG. 5
